SELF-CLAMPING BUCKLE

Leo Steiner, West Orange, N. J.

Application October 30, 1948, Serial No. 57,590

13 Claims. (Cl. 24—194)

1

My present invention relates to self-clamping buckles, and more particularly to buckle constructions for varying the operative length of a strap.

It is an object of my present invention to provide self-clamping buckles which will stay firmly in adjusted position so as to preclude any accidental change in the operative lengths of the straps.

Furthermore, it is another object of my present invention to provide self-clamping buckles which can be easily adjusted, i. e. easily loosened and moved to another position on the strap, when it is desired to increase or to shorten its operative length.

In accordance with my present invention, a self-clamping buckle for varying the operative lengths of a strap comprises in combination a wedge-shaped sleeve member through which said strap might be passed, and a wedge-shaped clamping member arranged within the wedge-shaped sleeve member slidably in contact with the same.

A preferred buckle construction of the type proposed by me includes a wedge-shaped sleeve member and a hollow wedge-shaped clamping member having a narrower end portion, and a wider end portion, and arranged within the passage in said wedge-shaped sleeve member with the narrower end portion located in the narrower end of the passage, and the wider end portion located in the wider end of the passage slidably in contact with the inner face of the other of said flat sleeve portions.

Furthermore, I have found it advisable to provide stop means on at least one of the members for preventing the wedge-shaped clamping member from sliding out of the wedge-shaped sleeve during operation of the self-clamping buckle.

Instead of using stop means of the above type it is possible to use a flexible connecting member attached at one end to the wedge-shaped sleeve and at the other end to the wedge-shaped clamping member, preventing the wedge-shaped clamping member from entirely sliding out of the wedge-shaped sleeve, without, however, interfering with its sliding within the sleeve.

In order to enable operation of the buckle with one hand only, I provide a pulling member e. g. a pulling tape secured to the wedge-shaped clamping member permitting sliding of the same out of the wedge-shaped clamping member until prevented from further sliding by the flexible connecting member or by the stop means.

In accordance with another embodiment of my

2

present invention, I provide slots in the wedge-shaped clamping member arranged parallel to the clamping edges thereof, and a combined connecting and pulling tape secured to the wedge-shaped clamping member and passing through the slots in such a manner as to enable said wedge-shaped clamping member to be slid by pulling of the tape relative to the wedge-shaped clamping member without sliding out of the same.

10 The novel features which I consider as characteristic for my invention are set forth in particular in the appended claims. The invention itself, however, both as to its construction and its methods of operation, together with additional advantages and objects thereof, will be best understood from the following description of specific embodiments when read in connection with the accompanying drawings, in which:

Fig. 1 is a front view of a suspender provided 20 with a self-clamping buckle of the type proposed by me;

Fig. 2 is a section through the arrangement shown in Figure 1, along line 2—2 of Figure 1, with the buckle in clamping position;

25 Fig. 3 is a section similar to the one shown in Figure 2, with the buckle in inoperative position;

Fig. 4 is a top view of the wedge-shaped clamping member forming part of the buckle shown in Figures 1 to 3, seen in direction of arrow 4, of Figure 3;

30 Fig. 5 is an elevational section through a modified buckle construction;

Fig. 6 is an elevational section through another modified buckle construction according to my present invention;

35 Fig. 7 is an elevational section through still another modified buckle construction according to my present invention;

Fig. 8 is an elevational section through a further modified buckle construction according to my present invention;

40 Fig. 9 is a side view of the buckle shown in Fig. 8;

Fig. 10 is a perspective view of the movable wedge member of the buckle of Figs. 8 and 9; and

Fig. 11 is a side elevation of the sleeve of the same Figs. 8 and 9.

The buckle construction shown in Figures 1 to 4 includes a wedge-shaped sleeve 10 having flat sleeve portions 11 and 12, forming an acute angle with each other. This sleeve 10 forms a passage 13 which is open at both ends, namely at its wider end 14, and at its narrower end 15.

55 My new buckle includes also a wedge-shaped

3

clamping member 16 provided with a main portion 17 adapted to lie superimposed upon the inner face of the sleeve portion 11 and to slide in the directions indicated by the double arrow 18 along the same, and two bent clamping portions, namely the wider clamping portion 19, and the narrower clamping portion 20.

In order to operate my new buckle, I provide a combined connecting and pulling tape 21 secured at its one end 22 to the sleeve portion 11, and passing through the slots 23 and 24, provided in the wedge-shaped clamping member 16.

Sliding out of the wedge-shaped clamping member 16 from sleeve 10 is prevented by the stop knob 25 firmly secured to the projecting portion 26 of tape 21, in such position that the wider clamping portion 19 of the wedge-shaped clamping member 16 abuts against it as shown in Figure 2 when the clamping member is moved into its uppermost operative position.

The elastic strap 27 holding the suspender straps 28 is secured by the strap sleeve 29 to the sleeve portion 12 of the buckle as clearly shown in Figures 2 and 3. This elastic strap 27 forms a loop 30 extending downwardly, and then again passes through the buckle sleeve 10 between the wedge-shaped clamping member 16, and the sleeve portion 12 of the buckle.

The clamping buckle described above operates as follows:

In the position shown in Figure 2, the buckle is in engaging position, preventing sliding of strap 27 relative to the buckle. As clearly shown in this figure, the operative edges 31 and 32 of the bent portions 20 and 19 respectively of the wedge-shaped clamping member 16, firmly engages the strap 27, preventing sliding of the same in the directions indicated by the double arrow 33.

In order to disengage the wedge-shaped clamping member 16 from the strap 27, the same is pulled from its position shown in Fig. 2 by means of the pulling member 21 in direction of arrow 34 into the position shown in Fig. 3 in which the engaging edges 31 and 32 either do not at all engage the surface of strap 27 or engage it only sufficiently to cause automatic clamping whenever the strap is pulled in upward direction.

I wish to note that during such pulling of the member 21 first the sleeve 10 is lifted from the clamping member 16 and as consequence thereof the clamping member is able to slide in downward direction.

The entire buckle is pulled by the member 21 downward until it reaches the desired position. Release of the buckle in this position will result in automatic clamping of the member 19 and prevention of further sliding of the buckle.

If it is desired to adjust the buckle in upward direction the pulling member 21 is simply pulled in upward direction. Such pull will first result in disengagement of the sleeve 10 and clamping member 16 and then in sliding of the entire buckle in upward direction. Release of the pulling member 21 in the desired final position will also in this event result in automatic stopping of the buckle.

Similarly, if it is desired to adjust the buckle downward, it is not necessary to pull first the pulling tape 21, and then the sleeve 10, but it is possible to simply pull by means of the pulling tape 21, the entire buckle downward into the desired position. The moment the pulling member is released in such desired position, the buckle

4

members will automatically move back into the clamping position shown in Figure 2.

I wish to note that in order to prevent sliding of the clamping member 16 too far into sleeve 10, I provide on the upper face of the clamping member 16, stop buttons 35 abutting against the edge 36 of the sleeve portion 11, when the buckle members are in their clamping position shown in Figure 2.

In Figure 5 I have shown a modified buckle:

The wedge-shaped sleeve member 37 is similar to the corresponding sleeve member of the buckle shown in Figures 1 to 4, and the general shape of the clamping member 38 is the same as the shape of the clamping member 16 of that buckle:

However, in order to prevent sliding out of the clamping member 38 from sleeve 37, I do not provide tape 21, but a hook member 39 provided on the clamping member 38, and adapted to engage the upper edge 40 of sleeve 37 as shown. Additionally, I provide also on the clamping member 38, an operating extension 41 by which it is possible to pull, i. e. slide the clamping member relative to sleeve 37.

Also in the embodiment shown in Figure 6, the sleeve 42, and the clamping member 43, have the same general shape. In this embodiment however, I provide simply a projection 44 on top of the clamping member 43 to prevent its sliding out from sleeve 42, and I attach at the lower end of the clamping member 43 a short tape 45 for pulling the clamping member downward, out of engagement with sleeve 42.

The buckles shown in Figures 5 and 6 are moved upward in exactly the same manner as the buckle shown in Figures 1 to 4, namely, by seizing the sleeve member and pulling it in upward direction.

The buckle shown in Fig. 7 is in basic respects similar to the buckle shown in Figs. 5 and 6. The main difference compared with the buckle shown in Fig. 6 is that the pulling tape is not secured directly to the wedge-shaped member, but that it is secured to pin 46 arranged inside the wedge-shaped member freely slidably in the directions indicated by the double arrow 47.

This pin is held inside the wedge-shaped member by two bridge-shaped portions 48 of the wedge limiting the width of the slot 49. The pulling tape 50 is secured to the pin 46 as shown.

It is evident that in order to adjust the buckle in downward direction it is only necessary to pull the tape 50 downward.

If it is desired to adjust the buckle in upward direction, it is also advisable to pull only the tape 50 in upward direction. Such upward pulling of tape 50 will result in exertion of pressure by the tape on the bottom edge 51 of the sleeve 42, pushing the same in upward direction, and thereby pulling the wedge-shaped member out of the sleeve and releasing its grip upon the strap 27. After the wedge-shaped member is released, it is easily possible to pull by means of the pulling member 50 the entire buckle upward into the desired position.

The buckle shown in Figs. 8 to 11 is a particularly preferred embodiment of my present invention. This embodiment is very similar to the buckle shown in Fig. 7, the only difference being that the pulling tape 52 is attached to the wedge-shaped member not by means of a pin, but directly secured at 53 to the inner face 54 thereof. It is evident that an arrangement of this type results in much greater pressure of the

tape 52 against the bottom edge 55 of sleeve 56 when the tape is pulled in upward direction.

As shown in Fig. 9, undesired slipping out of the wedge-shaped member from its sleeve in downward direction is prevented by the pin shaped projections 57 arranged in the plane of the main portion 58 of the wedge-shaped member at both lateral edges thereof. These projections engage corresponding cut-outs 59 arranged in the side faces of the sleeve member 56.

I wish to note that the stop members shown in the various embodiments of my new buckles are preferably triangular in cross section, so as to have a certain clamping effect upon the wedge-shaped member.

Furthermore, it should be stressed that in all embodiments of my invention the wedge-shaped member is hollow, i. e. bent out of one piece of sheet metal, and the upper gripping portion thereof designated in Figures 1, 2 and 3 with 20 has to be shaped so as to project in operative position well beyond the basic vertical plane of strap 21, so as to bend the same as clearly shown in Fig. 2.

Finally, I wish also to stress that the engaging edges of the wedge-shaped members proposed by me are preferably not sharp or serrated so as not to damage the strap.

It will be understood that each of the elements described above, or two or more together, may also find a useful application in other types of buckle constructions differing from the types described above.

While I have illustrated and described the invention as embodied in buckles for suspenders, I do not intend to be limited to the details shown, since various modifications and structural changes may be made without departing in any way from the spirit of my invention.

Without further analysis, the foregoing will so fully reveal the gist of my invention, that others can by applying current knowledge readily adapt it for various applications without omitting features that, from the standpoint of prior art, fairly constitute essential characteristics of the generic or specific aspects of this invention, and therefore, such adaptations should and are intended to be comprehended within the meaning and range of equivalence of the following claims.

What I claim as new, and desire to secure by Letters Patent is:

1. A self-clamping buckle for varying the operative length of a strap, including the combination of a wedge-shaped sleeve member of predetermined length comprising two rigidly connected oppositely arranged unyielding sleeve walls disposed at an acute angle to each other to form a passage between them which is wider at one end and narrower at the other end and through which the strap may be passed while superimposed upon one of the sleeve walls; a wedge-shaped clamping member of relatively greater length having a narrower clamping end portion and a wider clamping end portion and an intermediate portion interconnecting the clamping end portions and located slidably in contact with the other of said sleeve walls within the passage in said sleeve member, said clamping member having the narrower clamping end portion thereof located in the narrower end of said passage and projecting therefrom in one direction and the wider clamping end portion thereof located in the wider end of said passage and projecting therefrom in the opposite direction; and stop means fixed upon the clamping member at the narrower clamping end portion thereof and projecting into obstructing position against a portion of the sleeve member to prevent loss of said clamping member from the latter sleeve member when said clamping member is shifted to released position during operation of said clamping buckle.

clamping end portion thereof within the extremity of the latter and projecting into obstructing position against a portion of the sleeve member to prevent loss of said clamping member from the latter sleeve member when said clamping member is shifted to released position during operation of said clamping buckle.

2. A self-clamping buckle for varying the operative length of a strap, including the combination a wedge-shaped sleeve member of predetermined length comprising two rigidly connected oppositely arranged unyielding sleeve walls disposed at an acute angle to each other to form a passage between them which is wider at one end and narrower at the other end and through which the strap may be passed while superimposed upon one of the sleeve walls; and a wedge-shaped concavely hollow clamping member of relatively greater length having a narrower clamping end portion and a wider clamping end portion and located with the convex side thereof slidably in contact with the other of said sleeve walls within the passage in said sleeve member, said clamping member having the narrower clamping end portion thereof located in the narrower end of said passage and the wider clamping end portion thereof located in the wider end of said passage and being of sufficient length to project said narrower and wider clamping end portions simultaneously in opposite directions from the ends of said sleeve member.

3. A self-clamping buckle for varying the operative length of a strap, including the combination of a wedge-shaped sleeve member of predetermined length comprising two rigidly connected oppositely arranged unyielding sleeve walls disposed at an acute angle to each other to form a passage between them which is wider at one end and narrower at the other end and through which the strap may be passed while superimposed upon one of the sleeve walls; a wedge-shaped concavely hollow clamping member of relatively greater length having a narrower clamping end portion and a wider clamping end portion and an substantially straight intermediate portion interconnecting the clamping end portions and located slidably in contact with the other of said sleeve walls within the passage in said sleeve member, said clamping member having the narrower clamping end portion thereof located in the narrower end of said passage and the wider clamping end portion thereof located in the wider end of said passage and being of sufficient length to project said narrower and wider clamping end portions simultaneously in opposite directions from the ends of said sleeve member; and stop means fixed upon the clamping member at the narrower clamping end portion thereof and projecting into obstructing position against a portion of the sleeve member to prevent loss of said clamping member from the latter sleeve member when said clamping member is shifted to released position during operation of said clamping buckle.

4. A self-clamping buckle for varying the operative length of a strap, including the combination of a wedge-shaped sleeve member of predetermined length comprising two rigidly connected oppositely arranged unyielding sleeve walls disposed at an acute angle to each other to form a passage between them which is wider at one end and narrower at the other end and through which the strap may be passed while superimposed upon one of the sleeve walls; a wedge-shaped clamping member of relatively greater

length having a narrower clamping end portion and a wider clamping end portion and an intermediate portion interconnecting the clamping ends and located slidably in contact with the other of said sleeve walls within the passage in said sleeve member, said clamping member having the narrower clamping end portion thereof located in the narrower end of said passage and the wider clamping end portion thereof located in the wider end of said passage and being of sufficient length to project said narrower and wider clamping end portions simultaneously in opposite directions from the ends of said sleeve member; and manually operated pulling means secured to said wedge-shaped clamping member and depending from within the extremity of the wider clamping end portion thereof for slidably shifting said clamping member through the wedge-shaped sleeve member a sufficient distance to release the clamping end portions of said clamping member from said strap.

5. A self-clamping buckle for varying the operative length of a strap, including the combination of a wedge-shaped sleeve member of predetermined length comprising two rigidly connected oppositely arranged unyielding sleeve walls disposed at an acute angle to each other to form a passage between them which is wider at one end and narrower at the other end and through which the strap may be passed while superimposed upon one of the sleeve walls; a wedge-shaped clamping member of relatively greater length having a narrower clamping end portion and a wider clamping end portion and an intermediate portion interconnecting the clamping end portions and located slidably in contact with the other of said sleeve walls within the passage in said sleeve member, said clamping member having the narrower clamping end portion thereof located in the narrower end of said passage and the wider clamping end portion thereof located in the wider end of said passage and being of sufficient length to project said narrower and wider clamping end portions simultaneously in opposite directions from the ends of said sleeve member; stop means fixed upon the clamping member at the narrower clamping end portion thereof and projecting into obstructing position against a portion of the sleeve member to prevent loss of said clamping member from the latter sleeve member when said clamping member is shifted to released position during operation of said clamping buckle, the wedge-shaped clamping member having a slot in the wider end portion thereof; and manually operated pulling means secured to said wedge-shaped clamping member and depending from the latter through the slot therein for slidably releasing said clamping member through the wedge-shaped sleeve member when releasing the clamping end portions of said clamping member from said strap.

6. A self-clamping buckle for varying the operative length of a strap, including the combination of a wedge-shaped sleeve member of predetermined length comprising two rigidly connected oppositely arranged unyielding sleeve walls disposed at an acute angle to each other to form a passage between them which is wider at one end and narrower at the other end and through which the strap may be passed while superimposed upon one of the sleeve walls; a wedge-shaped concavely hollow clamping member of relatively greater length having a narrower clamping end portion and a wider clamping end portion and a substantially straight intermediate portion

interconnecting the clamping end portions and located slidably in contact with the other of said sleeve walls within the passage in said sleeve member, said clamping member having the narrower clamping end portion thereof located in the narrower end of said passage and the wider clamping end portion thereof located in the wider end of said passage, the wedge-shaped clamping member also having a slot in the wider end portion thereof, and said clamping member being of sufficient length to project the narrower and wider clamping end portions simultaneously in opposite directions from the ends of said sleeve members; and manually operated pulling means secured to said wedge-shaped clamping member and depending from the latter through the slot therein for slidably releasing said clamping member through the wedge-shaped sleeve member when releasing the clamping end portions of said clamping member from said strap.

7. A self-clamping buckle for varying the operative length of a strap, including the combination of a wedge-shaped sleeve member of predetermined length comprising two rigidly connected oppositely arranged unyielding sleeve walls disposed at an acute angle to each other to form a passage between them which is wider at one end and narrower at the other end and through which the strap may be passed while superimposed upon one of the sleeve walls; a wedge-shaped concavely hollow clamping member of relatively greater length having a narrower clamping end portion and a wider clamping end portion and an intermediate portion interconnecting the clamping end portions and located slidably in contact with the other of said sleeve walls within the passage in said sleeve member, said clamping member having the narrower clamping end portion thereof located in the narrower end of said passage and the wider clamping end portion thereof located in the wider end of said passage and being of sufficient length to project the narrower and wider clamping end portions simultaneously in opposite directions from the ends of said sleeve member; stop means fixed upon the clamping member at the narrower clamping end portion thereof and projecting into obstructing position against a portion of the sleeve member to prevent loss of said clamping member from the latter sleeve member when said clamping member is shifted to released position during operation of said clamping buckle, the wedge-shaped clamping member also having a slot in the wider end portion thereof; and manually operated pulling means secured to said wedge-shaped clamping member and depending from the latter through the slot therein for slidably releasing said clamping member through the wedge-shaped sleeve member until the stop engages against said portion of said sleeve member when releasing the clamping end portions of said clamping member from said strap.

8. A self-clamping buckle for varying the operative length of a strap, including the combination of a wedge-shaped sleeve member of predetermined length comprising two rigidly connected oppositely arranged unyielding sleeve walls disposed at an acute angle to each other to form a passage between them which is wider at one end and narrower at the other end and through which the strap may be passed while superimposed upon one of the sleeve walls; a wedge-shaped clamping member of relatively greater length having a narrower clamping end portion and a wider clamping end portion and an

intermediate portion interconnecting the clamping end portions and located slidably in contact with the other of said sleeve walls within the passage in said sleeve member, said clamping member having the narrower clamping end portion thereof located in the narrower end of said passage and the wider clamping end portion thereof located in the wider end of said passage and being of sufficient length to project the narrower and wider clamping end portions simultaneously in opposite directions from the ends of said sleeve member; at least one projecting stop fixed on the wedge-shaped clamping member adjacent the wider clamping end portion thereof, the wider end of said wedge-shaped sleeve member having at least one corresponding notch forming a seat for receiving said stop to prevent loss of said clamping member from the latter sleeve member when said clamping member is shifted to released position during operation of said clamping buckle; and manually operated pulling means secured to said wedge-shaped clamping member and depending from within the extremity of the wider clamping end portion thereof for slidably shifting said clamping member through the wedge-shaped sleeve member a sufficient distance to release the clamping end portions of said clamping member from said strap.

9. A self-clamping buckle for varying the operative length of a strap, including the combination of a wedge-shaped sleeve member of predetermined length comprising two rigidly connected oppositely arranged unyielding sleeve walls disposed at an acute angle to each other to form a passage between them which is wider at one end and narrower at the other end and through which the strap may be passed while superimposed upon one of the sleeve walls; a wedge-shaped concavely hollow clamping member of relatively greater length having a narrower clamping end portion and a wider clamping end portion and an intermediate portion interconnecting the clamping end portions and located slidably in contact with the other of said sleeve walls within the passage in said sleeve member, said clamping member having the narrower clamping end portion thereof located in the narrower end of said passage and the wider clamping end portion thereof located in the wider end of said passage and being of sufficient length to project the narrower and wider end portions simultaneously in opposite directions from the ends of said sleeve member; at least one projecting stop fixed on the wedge-shaped clamping member adjacent the wider clamping end portion thereof, the wider end of said wedge-shaped sleeve member having at least one corresponding notch forming a seat for receiving said stop to prevent loss of said clamping member from the latter sleeve member when said clamping member is shifted to released position during operation of said clamping buckle.

10. A self-clamping buckle for varying the operative length of a strap, including the combination of a wedge-shaped sleeve member comprising two rigidly connected and oppositely arranged sleeve walls disposed at an acute angle to each other to form a passage between them which is wider at one end and narrower at the other end and through which the strap may be passed between the sleeve walls, one of the latter walls forming a rear wall and the other forming a forward wall upon said sleeve member; a wedge-shaped clamping member having a narrower clamping end portion and a wider clamping end

portion and located slidably in contact with the forward sleeve wall within the passage in said sleeve member, said clamping member having the narrower clamping end portion thereof located in the narrower end of said passage and the wider clamping end portion thereof located in the wider end of said passage; at least one stop fixed upon the clamping member at the narrow clamping end portion thereof and projecting into obstructing position against a portion of the sleeve member to prevent loss of said clamping member from the latter sleeve member when said clamping member is shifted to released position during operation of said clamping buckle, said wedge-shaped clamping member having a downwardly open slot in the wider end portion with the upper end of the slot extending upwardly within the lower edge of the forward wall at the wider end portion of said sleeve member in all operative positions of the latter; a pair of stops on the wider end of said wedge-shaped clamping member which exert a gradually increasing pressure toward the wider clamping end portion increasing to a final terminal stopping effect; and manually operated pulling means secured to said wedge-shaped clamping member and depending from the latter through the downwardly open slot therein whereby upward pulling of said pulling means exteriorly of the forward wall of said sleeve member effects release of said clamping member by causing the sleeve member to slip easily off said clamping member with the clamping end portions of the latter anchored on said strap, both of the clamping end portions of said clamping member in all operative positions of the latter projecting exteriorly beyond the corresponding end edges of the rear wall of said sleeve member, and said pulling member when pulled downwardly through said sleeve member with simultaneous release of the clamping end portions of said clamping member from said strap.

11. A self-clamping buckle for varying the operative length of a strap, including the combination of a wedge-shaped sleeve member comprising two rigidly connected and oppositely arranged sleeve walls disposed at an acute angle to each other to form a passage between them which is wider at one end and narrower at the other end and through which the strap may be passed between the sleeve walls, one of the latter walls forming a rear wall and the other forming a forward wall upon said sleeve member; a concavely hollow wedge-shaped clamping member having a narrower clamping end portion and a wider clamping end portion and located with the convex side thereof slidably in contact with the forward sleeve wall within the passage in said sleeve member, said clamping member having the narrower clamping end portion thereof located in the narrower end of said passage and the wider clamping end portion thereof located in the wider end of said passage; means for preventing loss of the wedge-shaped clamping member from the sleeve member when the clamping member is shifted to released position during operation of said clamping buckle, said wedge-shaped clamping member having a downwardly open slot in the wider end portion with the upper end of the slot extending upwardly within the lower edge of the forward wall at the wider end portion of said sleeve member in all operative positions of the latter; a pair of stops on the wider end portion of said wedge-shaped clamping member which exert a gradually increasing pressure toward the

wider clamping end portion increasing to a final terminal stopping effect; and manually operated pulling means secured to said wedge-shaped clamping member and depending from the latter through the downwardly open slot therein whereby upward pulling of said pulling means exteriorly of the forward wall of said sleeve member effects release of said clamping member by causing the sleeve member to slip easily off said clamping member with the clamping end portions of the latter anchored on said strap, both of the clamping end portions of said clamping member in all operative positions of the latter projecting exteriorly beyond the corresponding end edges of the rear wall of said sleeve member, and said pulling member when pulled downward slidably releasing said clamping member downwardly through said sleeve member with simultaneous release of the clamping end portions of said clamping member from said strap.

12. A self-clamping buckle for varying the operative length of a strap, including the combination of a wedge-shaped sleeve member comprising two rigidly connected and oppositely arranged sleeve walls disposed at an acute angle to each other to form a passage between them which is wider at one end and narrower at the other end and through which the strap may be passed between the sleeve walls, one of the latter walls forming a rear wall and the other forming a forward wall upon said sleeve member; a concavely hollow wedge-shaped clamping member having a narrower clamping end portion and a wider clamping end portion and located with the convex side thereof slidably in contact with the forward sleeve wall within the passage in said sleeve member, said clamping member having the narrower clamping end portion thereof located in the narrower end of said passage and the wider clamping end portion thereof located in the wider end of said passage; at least one stop fixed upon the clamping member at the narrow clamping end portion thereof and projecting into obstructing position against a portion of the sleeve member to prevent loss of said clamping member from the latter sleeve member when said clamping member is shifted to released position during operation of said clamping buckle, said wedge-shaped clamping member having a downwardly open slot in the wider end portion with the upper end of the slot extending upwardly within the lower edge of the forward wall at the wider end portion of said sleeve member in all operative positions of the latter; a pair of stops on the wider end portion of said wedge-shaped clamping member which exert a gradually increasing pressure toward the wider clamping end portion increasing to a final terminal stopping effect; and manually operated pulling means secured to said wedge-shaped clamping member and depending from the latter through the downwardly open slot therein whereby upward pulling of said pulling means exteriorly of the forward wall of said sleeve member effects release of said clamping member by causing the sleeve member to slip easily off said clamping member with the clamping end portions of the latter anchored on said strap, both of the clamping end portions of said clamping member in all operative positions of the latter projecting exteriorly beyond the corresponding end edges of the rear wall of said sleeve member, and said pulling member when pulled downward slidably releasing said clamping member downwardly.

through said sleeve member with simultaneous release of the clamping end portions of said clamping member from said strap.

13. A self-clamping buckle for varying the operative length of a strap, including the combination of a wedge-shaped sleeve member comprising two rigidly connected and oppositely arranged sleeve walls disposed at an acute angle to each other to form a passage between them which is wider at one end and narrower at the other end and through which the strap may be passed between the sleeve walls, one of the latter walls forming a rear wall and the other forming a forward wall upon said sleeve member; a concavely hollow wedge-shaped clamping member having a narrower clamping end portion and a wider clamping end portion and located with the convex side thereof slidably in contact with the forward sleeve wall within the passage in said sleeve member, said clamping member having the narrower clamping end portion thereof located in the narrower end of said passage and the wider clamping end portion located in the wider end of said passage; a stop fixed on the clamping member adjacent to the narrow clamping end portion thereof and projecting transversely of the direction of releasing movement of said clamping member into obstructing position against a portion of the sleeve member to prevent loss of said clamping member from the latter sleeve member when said clamping member is shifted to released position during operation of said clamping buckle, said wedge-shaped clamping member having a downwardly open slot in the wider end portion with the upper end of the slot extending upwardly within the lower edge of the forward wall at the wider end portion of said sleeve member in all operative positions of the latter; a pair of stops on the wider end portion of said wedge-shaped clamping member which exert a gradually increasing pressure toward the wider clamping end portion increasing to a final terminal stopping effect; and manually operated pulling means secured to said wedge-shaped clamping member and depending from the latter through the downwardly open slot therein whereby upward pulling of said pulling means exteriorly of the forward wall of said sleeve member effects release of said clamping member by causing the sleeve member to slip easily off said clamping member with the clamping end portions of the latter anchored on said strap, both of the clamping end portions of said clamping member in all operative positions of the latter projecting exteriorly beyond the corresponding end edges of the rear wall of said sleeve member, and said pulling member when pulled downward slidably releasing said clamping member downwardly through said sleeve member with simultaneous release of the clamping end portions of said clamping member from said strap.

LEO STEINER.
